METHOD AND DEVICE FOR USE ON WINDING MACHINES

Johannes Uytenbogaart, Berlin-Lichterfelde, Germany, assignor to North American Rayon Corporation, New York, N. Y., a corporation of Delaware

Application January 25, 1937, Serial No. 122,296

12 Claims. (Cl. 242—18)

The present invention relates to the winding of thread, yarn, etc., but more specifically has for its purpose to provide an improved winding method and arrangement for use with winding machines. It will be described as applied to a winding machine in which the spool and yarn body wound thereon rest on a rotating cylinder and are driven thereby.

In the winding of thread, yarn, etc., it is essential in many instances to wind the thread under an even tension throughout the winding operation. In order to accomplish this result it is necessary that the take-up speed of the thread be constant. As is well known, there are two methods for obtaining a constant speed of take-up. One method is to use a compensating gear arrangement whereby as the yarn body increases in diameter the speed of rotation of the winding spindle is reduced so that the peripheral speed of the yarn body remains constant. The second method makes use of the yarn body itself. The spool rests on a rotating cylinder and is driven thereby. By means of this latter method it is obvious that the peripheral speed of the yarn body remains constant and that further the necessity of having an expensive compensating gear arrangement is eliminated.

However, the use of yarn driven winding machines has certain disadvantages. In order to feed the thread to the spool it has been the custom to pass the thread between the driving roller and spool and from the traverse guide. Due to the reciprocative movement of the traverse guide the thread is continually dragged back and forth between the said driving roller and yarn body which naturally results in an excessive frictional wear and pull on the thread. Heretofore in the art, however, so far as applicant is aware, no satisfactory method or apparatus has been provided to overcome the aforementioned disadvantage.

Further, the starting of thread on any winding machine is frequently a problem. On yarn driven winding machines, if the thread is to be fed from the traverse guide to the top of the spool in order to eliminate the drag on the thread from the driving roller it is important, if not essential, that some thread feeding means be provided in order to start the thread on the spool at the beginning of the winding operation.

Another disadvantage in the use of winding machines which drive the yarn body is that at the end of the winding operation when the thread is broken from the source of supply, the loose end is unretained and is frequently thrown to

other parts of the winding machine, tangling therein and at times impairing the efficiency of these machines. It is also for the purpose of preventing such occurrences that applicant has devised his novel thread carrying device.

It is therefore one object of the present invention to devise a method and means for facilitating the feeding of thread to a spool at the beginning of the winding operation on winding machines.

Another object of the present invention is to devise a thread starting method and means for use on yarn driven winding machines whereby the thread may be fed more expeditiously to the top of the winding spool.

Still another object of the present invention is to devise a thread starting method and means for winding machines which will break the loose end of the thread from the winding spool, thus eliminating the chance of the said loose end from wrapping around the winding spindle.

A still further object of the present invention is to devise a method and apparatus for winding of yarn, filaments, threads, etc., whereby the loose end of the thread at the end of the winding operation is taken up.

These and other objects of the present invention will in part become obvious and will in part be pointed out in the following specification and appended claims when taken in conjunction with the attached drawing, in which,

Fig. 1 is a front elevation, part being shown in section, of a winding spool equipped with my device and a portion of a winding machine to illustrate the use thereof;

Fig. 2 is an end elevation of the parts shown in Fig. 1, and

Fig. 3 is a cross-sectional view taken on the line 3—3 of Fig. 1.

In the drawing, in which like numerals of reference indicate like parts, 1 and 2 indicate the bearing brackets of a winding machine (not shown).

The brackets 1 and 2 have grooves 3 and 4 into which the ends of the spool spindle 5 extend and ride therein as the yarn body 6 increases in diameter.

The yarn body 6 is wound on a spool body 7. The spool body or cylinder 7 may be mounted on a spool holder 8 such as is illustrated in the drawing. The spool holder 8 rotates around the spindle 5. The spindle 5 has flattened ends 5a which ride in the grooves 3 and 4, the said ends 5a preventing rotation of the shaft 5 while allowing the shaft to slide in the grooves as the yarn body increases in diameter. The spindle or 55

shaft 5 has mounted thereon a spacer sleeve 18 at either end of which are mounted ball bearing races 19 and 20. Ball bearings 21 rotate in the said races 19 and 20 and the spool holder 8 through the medium of bearing rings 22 and 23, rotates around the bearings 21. The spool holder 8 has end flanges 9 and 10 which support the spool 7 in centered position on the spool spindle 5.

The flange 9 is slidably mounted on the spool holder 8 and spring-held against the spool 7 by a spring 11.

The holder 8 and flange 9 are removable as a unit in order to remove the spool 7 from the spool holder.

15 The above structure has been described in greater detail in copending application Serial No. 122,297, filed January 25, 1937 entitled "Spindle support for spools".

20 Mounted on the spool holder 8 and rotatable therewith is a disc 12 which has notches 13 cut in the periphery thereof for a purpose to be explained later.

The spool 7 carried on the spool holder 8 rests on a driving cylinder 14 and is rotated thereby.

25 A traverse bar 15 and guide 16 for imparting the desired cross-wind to the yarn body is shown in section in Figure 2 of the drawing. It is of course apparent that other thread guide means may be used.

30 Ordinarily, as brought out previously in this specification, the thread coming from the traverse guide 16 is passed between the driving roller 14 and the spool and yarn body. As hereinbefore brought out this results in an excessive drag on the thread due to the pull of the traverse motion which frequently results in damaged thread and yarn bodies.

It has been found that the excessive drag of the thread caused by the movement of the traverse guide may be overcome by feeding the thread to the top of the yarn body or spool. In order to start the thread feed a notched disc 12 has been provided which rotates therewith.

35 The operator by taking the loose end of the thread in one hand and with the other hand placing a portion of the thread at the center of the spool body 7 runs the thread down onto the rounded peripheral edge of the disc 12, whereby it is caught in one of the notches 13, the edges 50 of which are also rounded to prevent unintentional tearing of the thread, and carried around therewith thus wrapping the thread around the spool 7 and starting the winding operation. It will be appreciated from a consideration of Figs. 1 and 2 that the thread is supplied from below the traverse bar 15 and traverse guide 16, and, therefore, below the spool 7. With the arrangement of Fig. 1, the operator will ordinarily have the loose end of the thread in his left hand and the bend or loop, formed by the adjacent portion 60 of the thread and the supply coming up and over the bar 15, in his right hand for introduction to the top side of the rotatable spool 7. The loose end of the thread between the operator's hands and near his left hand will be run onto the edge of disc 12. As shown in Figs. 2 and 3 of the drawing, the notches 13 are nearly circular in shape, being set in from the edge of the disc 12 and provided with restricted openings which are 65

70 narrower than the bottom of the notches. While the loose end of a thread can easily slip into one of these notches over the rounded corners, the restricted opening will tend to retain it therein. By holding the loose end of the thread tightly 75 the excess end may be broken off and easily dis-

posed of and thereby eliminating wrappings around the spindle ends.

A guard rail 17 may be mounted on the bearing bracket 1 adjacent the disc 12 transverse to the winding means. The purpose of this guard 5 rail is twofold, it acts as a guard to protect the operator and also acts as a guide to lead the thread down to the periphery of the disc 12.

At the end of the winding operation when the thread is to be broken for the purpose of removing the filled spool, it is drawn across the edge of the disc 12 and allowed to catch in one of the notches 13 in order to wrap it around the end of the spool holder. The thread may be broken by holding it as the disc rotates. This 15 arrangement eliminates any possibility of the loose end being carried to other parts of the machine and causing operating troubles because of tangling thereof in working parts.

The advantages of the invention are thus 20 clearly apparent. By using this device on ordinary winding machines the starting feed of the thread is facilitated. By using the invention on yarn driven winding machines it will be found no longer necessary to introduce the thread between driving roller and yarn body thus resulting in an improved yarn body and eliminating excessive friction, so injurious to the thread 25 quality.

It is apparent that other means may be mounted 30 on the disc 12 for carrying the thread.

While I have described my method and apparatus particularly as it relates to use with yarn driven winding machines it will be readily apparent that it may be used to great advantage on other types of winding machines. Examples of such other types are spindle driven or bead driven spools or bobbins. It may also be used to advantage in a yarn driven winding machine in which the thread is fed directly between the driving 40 roller and the yarn body rotating therein.

From the foregoing description, taken in connection with the accompanying drawing it is thought the complete construction, operation and advantages of my invention will be clear to those 45 skilled in the art to which it relates.

What I claim is:

1. In winding machines for thread, yarn, etc., means to collect thread, and a disc means operative with said collecting means to facilitate the 50 feed of the thread at the beginning of the winding operation, said disc having a notch with a restricted opening and rounded edges.

2. In winding machines for thread, yarn, etc., a spool adapted for use thereon, and a disc mounted on said spool constructed and arranged to facilitate the feed of thread thereon at the beginning of the winding operation, said disc having a notch with a restricted opening and rounded 55 edges.

3. In winding machines for thread, yarn, etc., a spool adapted for use thereon, and a disc mounted on said spool constructed and arranged to facilitate the feed of thread thereon at the beginning of the winding operation, said disc being of a diameter greater than the diameter of the spool, said disc being provided with a notch having a restricted opening and rounded edges. 60

4. In winding machines for thread, yarn, etc., a winding element, and a notched disc mounted 70 for rotation therewith and adapted to facilitate the feed of the thread at the beginning of the winding operation, the notch in said disc being narrower at its opening than at its bottom and having rounded edges.

5. A winding spool for use on thread winding machines, and means mounted at one end thereof adapted to facilitate the feed of the thread at the beginning of the winding operation, said
5 means having a notch therein which is wider at its bottom than at its opening and is provided with rounded edges.

6. In winding machines for thread, yarn, etc., a rotatable winding means, and a disc mounted
10 thereon and rotatable therewith and of a diameter greater than the diameter of the winding means, said disc having a plurality of peripheral notches with restricted mouths adapted to facilitate the feed of thread at the beginning of the
15 winding operation and rounded edges.

7. In winding machines for thread, yarn, etc., a rotatable winding means, a member mounted for rotation with said winding means, said member having means thereon to pick up a thread,
20 and a fixed guide for guiding the thread onto the said member.

8. In winding machines for thread, yarn, etc., a rotatable winding means, a member mounted for rotation with said winding means, said member having abutments thereon adapted to pick up a thread, and a fixed guide extending transversely with respect to the winding means for guiding the thread onto the said member.

9. In winding machines for thread, yarn, etc.,
30 a frame, a rotatable winding means, a notched disc mounted thereon and rotatable therewith adapted to facilitate the feed of thread at the beginning of the winding operation, and means fixedly mounted on the frame of said winding
35 machine and adjacent said disc to guide thread onto the periphery of the said disc.

10. In the winding of threads the steps comprising, positioning a bend of thread opposite a rotating spool on which it is to be wound while causing the adjacent loose end of said thread to rotate with an end of the spool until the
5 thread has been carried around the spool, and severing a portion of said loose end by restraining its movement with respect to the rotating end of said spool.

11. In the winding of threads the steps comprising, positioning a bend of thread at the beginning of the winding operation opposite a rotating spool on which it is to be wound, concurrently causing a loose end of the said thread to rotate with an end of the spool until the thread
15 has been carried around the spool, severing a portion of said loose end, winding the thread to form a yarn body on said spool, and severing the thread from the yarn body.
20

12. In the winding of threads the steps comprising, rotating a spool by a rotor contacting with the surface on which the thread is to be wound, positioning a bend of thread opposite the spool intermediate its ends while causing the
25 adjacent loose end of said thread to rotate with an end of said spool so as to feed thread to be wound in a direction opposed to the direction of travel of the surface of the rotor contacting the surface on which the thread is to be wound,
30 and severing a portion of said loose end by restraining its movement with respect to the rotating end of said spool.

JOHANNES UYTENBOGAART. 35
